POWDER PUFF

Louine Miller Fox, New York, N. Y.

Application August 1, 1946, Serial No. 687,742

1 Claim. (Cl. 15—209)

1

This invention relates to powder puffs and in particular to a puff that facilitates the application of powder.

A particular object of the invention is to provide a puff construction in which a handle portion is provided so that the face patting pad section of the puff may be employed with a slapping action to apply powder to the face or other body surfaces.

Further objects of the invention provide for the construction of a powder puff, made solely of fabric, that is easy to handle and use and in which waste of powder will be reduced to a minimum and in which the material employed will be extremely soft and pliable; to provide a puff construction having a handle portion that may be grasped and relatively to which the powder puff portion will be swingable to provide patting action necessary in applying the powder; to further provide a reinforcement within a handle portion of the puff so that the patting action of the powder applying pad will be increased; and to provide for the relative arrangement of the handle and puff sections so that when not in use, the handle portion may be folded against the front of the puff to cover and protect the face patting surface thereof.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

Fig. 1 is a view in front elevation of a powder puff constructed in accordance with my invention.

Fig. 2 is a view in rear elevation of the puff illustrated in Fig. 1, the hand hold ribbon being shown in connection with the puff portion thereof.

Fig. 3 is a vertical section taken on the line 3—3 of Fig. 1 showing the construction of the powder puff.

Fig. 4 is a section taken on the line 4—4 of Fig. 2 showing the inturned construction of the pad portion of the powder puff.

Fig. 5 is a diagrammatic plan view of the material blank from which the powder puff is constructed.

Fig. 6 is a view in front elevation, similar to Fig. 1, of a powder puff of modified construction.

Fig. 7 is a vertical section on the line 7—7 of Fig. 6 showing the interior construction of the puff.

2

Fig. 8 is a view in front elevation of a powder puff in which the parts are arranged for relative folding relation.

Fig. 9 is a view similar to Fig. 8 showing the handle portion of the puff folded against the face thereof to provide a covering therefor.

Fig. 10 is a view in side elevation of the folded puff illustrated in Fig. 9.

Referring to Figs. 1 to 5 inclusive the powder puff structure indicated generally as at 10 consists of a front 11 and a back 12 preferably formed from a blank 13 of lamb's wool or other powder retaining material that is used for applying powder by patting or slapping action, the blank 13 being turned in at its edges as at 14 in its front and rear sections and sewn as at 15 to form a powder puff of substantially heart shaped contour.

The upper enlarged portion of the structure 20 constitutes a face patting pad or puff 16 while the lower tapered portion constitutes a handle 17. These two portions are divided and formed by the line of stitching 18 extending across the puff and joining the front and rear sections 11 and 12 respectively. The line of stitching 18 performs several functions. It provides a hinge so that when the handle portion is grasped, the pad portion 16 may be given a swinging motion so that the powder may be applied by a patting or slapping action and thus distributed evenly. Another function of the stitching 18 is that it holds the filler 20 mid-way of the pad structure and prevents it from shifting vertically relative to the outer cover and consequently preserves an even thickness of pad throughout the face patting portion and the handle thereof. The filler may be made of felt, cotton or other cellular material that will give sufficient body to the pad to provide for the proper application of the powder.

40 In order that the powder may be applied without the use of the handle 17 the inturned vertical edges 14 of the blank have sewn between them, the ends 21 of a band or holding ribbon 22 beneath which the fingers may be inserted to hold 45 the pad in powder applying operation.

In this form of the invention, as in the forms to be described, the handle is held and the hinge portion provided by the sewing 18 will permit the pad portion to be swung to provide the necessary powder applying slapping action.

Referring to Figs. 6 and 7 the pad 10 is made in substantially the same manner as is the pad illustrated in Figs. 1 to 5 employing the same blank 12 providing the front and rear portions 11 and 13 respectively which, when sewn together

as at 25 on their inturned edges 26, may hold between them in the lower or handle portion 27 of the puff structure a piece of stiffening material 28 such as buckram or the like which is also engaged by the stitching 29 across the middle portion of the puff that defines the hinge or break 30 between the handle 27 and the face padding pad 31.

The face pad portion 31 has secured thereto the hand hold ribbon 32 which is connected by the stitching 25 within the inturned edges 26 of the puff material. In this form of the invention the hinging action is further accentuated by the creviced side edges of the puff structure as at 33 which are located at the terminals of the sewing 29. This puff structure provides a relatively larger face engaging portion 31 than a handle 27; this feature being applicable also to the structure of the puff illustrated in Figs. 1 and 2.

Referring to Figs. 8 to 10, the puff may be shaped to provide a face portion 34 and a handle portion 35 of substantially like areas, the face portion 34 carrying the ribbon 36 which is attached thereto in the manner described, it being understood that in this structure the stiffening agent 28 may be employed if desired. The relative areas of the face and handle portions 34 and 35 respectively and the use of the ribbon 36 in connection with the face portion 34 permit the handle 35 to be folded as illustrated in Fig. 9. The ribbon 36 holds the two sections together in close contact whereby the puff can be placed in a compact or other limited space.

Having thus described my invention, what I claim as new, and desire to secure by United States Letters Patent is:

In a powder puff having an elongated hollow body enclosing a filler pad, inwardly projected crevices formed in diametrically opposite sides of the body in lateral alignment with each other, 5 a single line of stitches extended laterally across the body between the inner ends of the crevices dividing the puff into a larger padding portion and a smaller handle portion and forming a hinge line between the portions, a piece of stiffening material within said handle portion stiffening the same, said piece of stiffening material having an edge portion adjacent said padding portion extended into said padding portion and through which said stitches pass so as to reduce the flexibility of said hinge line to retain said padding portion on a common plane with said handle portion, and a handle ribbon secured in position across one face of said padding portion parallel to said line of stitches and substantially 15 mid-way between said line of stitches and the free end of said padding portion.

LOUINE MILLER FOX.
